DESIGN FOR A HIP PROTECTOR

Charles A. De Ware, College Station, Tex.

Application September 10, 1940, Serial No. 94,927

Term of patent 7 years

To all whom it may concern:

Be it known that I, Charles A. De Ware, a citizen of the United States, residing at College Station, in the county of Brazos and State of Texas, have invented a new, original, and ornamental Design for Hip Protector, of which the following is a specification, reference being had to the accompanying drawings, forming part thereof.

Fig. 2 is a rear view of the hip protector illustrated in Fig. 1; and

Fig. 3 is a front view of the hip protector shown in Figs. 1 and 2.

I claim:

The ornamental design for a hip protector, as shown.

CHARLES A. DE WARE.
